ROWING DEVICE

John A. Kashev, Chicago, Ill., assignor to
 John W. Sereda, Chicago, Ill.
 Filed Sept. 12, 1962, Ser. No. 223,052
 2 Claims. (Cl. 9—25)

This invention relates to a novel rowing device and in particular relates to a novel oar construction the primary object of which is to permit a boat to be rowed or propelled in the same direction as the rorer faces, even though the latter exerts the normal pull rather than push on the oar handles.

Another object of this invention is to provide an oar construction in which the blade of the oar moves in the same relative direction as the push or pull exerted by the oar handle.

Another object of this invention is to provide an oar construction which will permit the rorer to propel the boat in the direction in which he is facing so that he can always see where he is going and determine what obstacles are in the path of the boat.

It is a further object of this invention to provide a simple and effective rowing mechanism so constructed and arranged that the rorer can sit facing the bow of the boat as he manipulates such mechanism.

It is also a further object of this invention to provide a mechanism of this type in which the blade portion of the oar can be folded up closely to the sides of the boat or the same readily detached from the side of the boat and collapsed when desired.

It is another object of this invention to provide an oar having a blade portion and a handle portion such that the blade portion will be reciprocated in the same directions to the movements of the handle portion providing a divided oar member, such divided oar member being pivotally journaled on the gunwale guide or support of the boat.

It is another object of this invention to provide a rowing mechanism whereby the oar is pivotally mounted to permit the rorer to face the bow and to provide easy raising and lowering of the oar into the water to obtain maximum push or pull of the boat due to proper inclination of the blade with respect to the boat and its position in the water.

Another object of this invention is to provide a bow-facing oarlock in which the plane of the blade of the oar during its movement through the water will be perpendicular to the surface of the water so that practically all of the energy applied thereto will be utilized in propelling the boat.

Another object is to provide a device of the character described of light, simple construction which may be readily attached to any boat and which may be conveniently collapsed or folded to facilitate transportation.

It is another object of this invention to provide a rowing mechanism for propelling boats by a manner known as a forward-rowing construction in which the operator faces forward in the boat and propels the boat forwardly by means of a rearward pull on the oars.

Another object of this invention is to propel a novel oar structure designed for either forward or backward rowing and readily convertible from one type to the other.

Another object of this invention is to provide an oar structure for both forward and backward rowing, and in which the necessary up-and-down angular movement of the oar for dipping the blade into and lifting it from the water is provided in either of the manners of use of the oar.

Another object of the invention is to provide an oar of the above kind that is of simplified, yet durable, construction and especially desirable for pleasure craft.

2

Other objects of the invention reside in the details of construction of parts, in their combination and mode of use, as will hereinafter be fully described. However, it is to be understood that changes in size and proportion of parts may be made and various materials may be employed in their construction without departing from the spirit of the invention, and therefore it is not desired that the claims appended hereto shall be limited in this respect but they shall be given an interpretation that is commensurate with the scope of the invention disclosed herein.

In accomplishing the above-listed and other objects of the invention, I have provided the improved details of construction, the preferred form of which is illustrated 15 in the accompanying drawing, wherein:

FIGURE 1 is a sectional top view of a row boat, employing my novel rowing mechanism;

FIGURE 2 is an enlarged sectional view illustrating my novel rowing mechanism or construction for the right 20 side of the boat;

FIGURE 3 is a sectional view of the novel rowing mechanism in a locked or out-of-use position;

FIGURE 4 is an enlarged sectional view of the right side of the boat looking from the inside out and taken 25 along line 4—4 of FIGURE 2;

FIGURE 5 is an outside perspective view of the right side of a portion of the boat and illustrating the novel mounting mechanism for my novel oar or rowing construction; and

30 FIGURE 6 is a sectional view taken substantially along line 6—6 of FIGURE 5 and illustrating the oar fastening mechanism.

With reference now to the drawings there is shown a rowboat, generally indicated as 1, having stern 2, port 35 side 3, starboard side 4, and bow portion 5 (not shown completely), the boat 1 having port and starboard gunwales 6 and 7 mounting rowing devices or oar mechanisms 8 and 9 by oar lock structures 10 and 11 between the operator's or rorer's seats 12 and 13. In this respect it will be noted that though the rowing structures 8 and 9 are mounted toward the stern 2 they can be mounted also toward the bow 5 of the boat 1 as well. The oar devices 8 and 9 are identical in all respects and therefore discussion will be limited to the right or starboard oar structure 9 which comprises a blade portion 14 and a handle portion 15, the blade portion 14 having a blade 40 16 at the outer end and an inner gear portion 17 at the inner end having a cluster of teeth 18 circumferentially about a greater outer peripheral portion of gear 17, gear 17 being attached to blade element 14 by bolt means 20. The gear 17 has coupled to its upper surface 21 one end 21a of a link or plate 22 by bolt means 23 and gear 17 meshes with gear teeth 24 circumferentially arranged on gear portion 25 as in the case of gear portion 55 17 and the link 22 has its other end 26 connected to top surface 27 of gear 25 by bolt means 28, gear 25 being coupled to handle part 15 by bolts means 29. It is to be noted that the bolts 28 and 23 present a central pivot for their respective gears 17 and 25, each gear 17 and 25 rotating about its bolt 23 and 28 while their teeth 18 and 24 interlock or mesh with one another permitting the gear sections 17, 25 to carry coupled parts 14 and 15 together in unison in a forward or rearward direction. The bolts 60 23 and 28 present fixed pivots in that each passes through gears 17 and 25 and each passes through respective flanges or ears 31 and 30 of oar carriage plate or element 32 which supports the oar structure 9 carried in lock or bed 11 secured on the starboard gunwale 7.

65 The flanges or tabs 30 and 31 which carry or support the gear sections 25 and 17, are joined with the elongated U-shaped plate portion 33 of member 32 having a pair

of depending journal parts 34 and 35 apertured with openings 32a, 32b to present a pair of journals for elongated shaft 36 reciprocally mounted and rotatively journaled therein and limited in horizontal fore and aft shifting movement by pin 37 extending outwardly of shaft or bearing rod 36. The shaft or key 36 in elevational view as seen in FIGURE 4 has at its right end an arm or handle 37a extending generally outwardly and somewhat slightly downwardly and at right angles to shaft portion 38 of key 36. The key 36 is generally cylindrical or circular in its shape throughout but as seen in FIGURE 4 is provided with a ground flat or slotted portion 40 having 180° apart flat sides 41 and 42 disposed between trunnion portions 34 and 35 and has at its left end outwardly of trunnion 34 another flat 45 having 180° apart flat sides 43 and 44.

It is seen that the bed or oar carriage 11 comprises an angle iron having a downward depending part 45a bolted as at 46 (FIGURE 4) to inside right bulkhead 47 of boat 1 and having a flat horizontal plate portion 48 bolted as at 49 on the gunwale or top portion 7.

Projecting upwardly and secured to the top plate portion 48 of the carriage or oar catch are a pair of L-shaped members 50, 51 having flats 52, 53 bolted to element 11 and upright ears or trunnions 54 and 55 spaced a predetermined distance apart from one another to allow depending ears 34 and 35 of plate or brace 32 to be spaced within as shown in FIGURE 4, the upright trunnions 54 and 55 each having a respective pin cradle or key cradle or slot 56 and 57 respectively, the slots or keyways 56, 57 having each a pair of upright walls 58, 58 and a semi-circular or crescent shaped surface 62, 62 respectively, the surfaces 62, 62 being journals for the rotatable key or shaft 36 as seen in FIGURE 4 and the handle 37a being entrained in slot 63 formed between upright 54 and upright detent or stop 64 on flat 52 of L-shaped member 50 of the oar catch 11.

The link 22 has a drilled hole 65 and portion 33 of member 32 has drilled hole 66 aligned therewith for selective and alternate complementary fixing alignment or registry with drilled hole 67 or 68 or gear portion 25 of handle part 15 by insertion of key or pin 75 through opening 65, appropriate opening 67 or 68, and opening 66. If pin 75 is inserted through holes 65, 67, and 66, the gear portion 25 is in longitudinal alignment with gear portion 17 and presents a rigid oar member 14 wherein its parts 14 and 15 are rigid and can not move with respect to one another, allowing the oarsman to remove the oar in order to paddle with the oar in canoe fashion for propelling the boat. If oar 8 or 9 is collapsed in a folded position (FIG. 3), then pin 75 can be inserted into openings 65, 66, 68 to maintain the oar in compact out of use position whether the oar 8 or 9 is attached to its respective oar lock 10 and 11 or not.

Either oar construction or device 8 or 9 is assembled to its respective carriage or oar lock structure 10 or 11 as follows. The oar unit 8 or 9 is held in the hand with pin 75 removed and the key or lever 36 is inserted into keyways 62 such that flats 41, 42 of part 40 and flats 43, 44 of parts 45 are vertical with handle parts 37a upright to allow faces 41, 42, 43, 44 to pass between faces 58 of parts 54, 55 (as exemplified in FIG. 6 for the flat part 45), permitting round shaft 36 to be cradled in crescent shaped surfaces 62 of keyways 56, 57 whence bolt or key 36 is pushed forward toward bow of boat and rotated to place handle 37a down into slot 63, thus locking oar structure 9 to its oarlock or bracket 11 and preventing disengagement of key 36 from keyways 56, 57. By such an arrangement the member 32 of oar structure 11 is allowed to move to and fro and rotate in a vertical plane about shaft or coupler 36 and the oar section 15 can pivotally flex or jackknife in a generally horizontal or a common plane with respect to oar section 14 because of pivot bolts 23 and 28 and meshing of gears 17 and 25.

As seen in FIGURE 1 in dotted lines, as handle portion 15 is drawn toward the stern as the operator faces the bow, the oar unit has its outer portion 14 and blade 16 therewith drawn through the water in the same direction as the handle 15. Since the paddle portion 16 is drawn rearward through the water the boat is propelled forward in the direction the oarsman is facing as shown by arrows in FIGURE 1.

Since the oar rotated is in vertical planes the face of the blade or paddle is perpendicular with respect to the surface of the water and this results in maximum application of rowing force.

Thus what is disclosed here is a novel rowing device or oar unit that is uncomplicated in construction and conducive to manufacture and allows the oarsman to face the direction of rowing and to see in the direction the boat is moving. In the alternative the oarsman may lock the oar structure to act as a unitary or integrated rigid oar structure for rearward facing rowing in a conventional manner. This design also aids the oarsman in easy manipulation of the oars and permits maximum rowing output with a minimum of effort. This design also permits one to collapse the oars readily and simply for easy and compact storage of the oar when out of use.

In view of the foregoing description taken in conjunction with the accompanying drawings it is believed that a clear understanding of the device will be quite apparent to those skilled in this art. A more detailed description is accordingly deemed unnecessary.

It is to be understood however, that even though there is herein shown and described a preferred embodiment of the invention the same is susceptible to certain changes fully comprehended by the spirit of the invention as herein described and the scope of the appended claims.

What is claimed is:

1. A bow facing rowing device for a boat having an oar paddle section and an oar handle section, comprising interlocking means on the sections engaging one section with the other, link means pivotally connected with each section providing forward and rearward in unison motion of the sections with respect to one another in a common plane about an axis of each section, mounting means on the boat transverse to the sections, and removable key means being removably carried on the oar mounting means and being rotatively and reciprocally movable in the mounting means from a first unlocked position to a second locked position, and the link means being rotatively journaled with the key means in a plane transverse to the key means, said mounting means having a pair of spaced apart grooves, and said key means comprising a member extending transversely to said link means and having portions rotatably mounted in said grooves, each groove having an inner enlarged opening and an outer reduced opening, and said member having a pair of reduced parts each reduced part being complementary received in the reduced opening of a respective groove in the first position of the key means and having a pair of enlarged parts each enlarged part being complementary received in the enlarged opening of a respective groove in the second position of the key means attendant to locking the sections to the mounting means, and said key means having radial extension means engageable with the mounting means in the second position in limiting axial movement of the key means in the mounting means and preventing withdrawal of the key means from the mounting means.
2. A bow facing rowing device for a boat having an oar paddle section and an oar handle section comprising interlocking means on the sections engaging one section with the other, link means disposed on the gear sections and pivotally interconnecting the oar sections providing in unison fore and aft motion thereof in a common plane, oar bracket means mounted on the boat including a pair of elements spaced apart from one another and each element being provided with a groove, oar carriage means

having a pair of members and each member having an aperture in registry with a respective groove of the element, and key means removably extending through the apertures and the grooves and having locking portions extending in and reciprocally and rotatably extending through the apertures and grooves from a first unlocked position to a second locked position attendant to locking the elements with the members, and said key means having radial extension means engageable with the oar bracket means in the second position in limiting axial movement of the key means in the oar bracket means and pre-

venting withdrawal of the key means from the mounting means.
